FEELER MECHANISM FOR LOOMS

Clarence Richardson, Salem, N. H.

Application March 23, 1932. Serial No. 601,466

16 Claims. (Cl. 139--233)

This invention relates to electrical detector devices or feeler mechanisms for controlling the operation of looms in accordance with the condition of the weft or filling in the shuttle, and my improved feeler device disclosed herein is adapted for use with both single and double shuttle looms for arresting the operation of the loom when the filling in the shuttle is substantially exhausted and also for automatic looms to initiate the operation of the weft replenishing mechanism which presents a fresh supply of filling to the weaving when required. The primary object of the invention is to provide an improved, more reliable and more accurate feeler mechanism of this nature which functions by pressure directly against the bobbin to close an electric contact when the yarn on the bobbin has been reduced to a predetermined amount.

My improved feeler device is adapted to function by periodically engaging the bobbin in the shuttle and automatically closing an electric contact when the yarn on the bobbin has been reduced to a predetermined amount. It will be understood that to perform this function with accuracy requires delicate sensing mechanism for engaging the bobbin and a cooperating delicate functioning of the contact members. My invention gives particular consideration to these two important features by providing for an accurate adjustment thereof to a fine degree without in any manner affecting the other parts of the device. Another object of the invention is to provide a device having such adjustments whereby its functions are performed with greater accuracy and facility and resulting in the elimination of irregularities in the operation of looms and in the saving of large amounts of yarn which have heretofore been left on the bobbins.

Other novel features and advantages of my invention reside in the compact and substantial construction and arrangement of the operating parts of the device, the contacting elements preferably being elongated rods substantially housed in tubular members and movable as a unit therewithout closing the contacts, and cooperating means for permitting adjustment of the rods and other means for holding the parts in the normal operative position.

These and other features of the invention will be best understood and appreciated from the following description of a preferred embodiment thereof, selected for purposes of illustration and shown in the accompanying drawings, in which

matic loom showing my improved feeler device as applied to use with the filling replenishing mechanism;

Fig. 2 is a sectional view taken on line 2--2 of Fig. 1;

Fig. 3 is a vertical sectional view through one of the feeler devices shown in Figs. 1 and 2;

Fig. 4 is a cross sectional view thereof on line 4--4 of Fig. 3;

Fig. 5 is a side elevation of a modified form of the device, a portion of the housing being broken away;

Fig. 6 is a sectional view therethrough taken on line 6--6 of Fig. 5;

Fig. 7 is an enlarged fragmentary sectional view of a portion of the device shown in operation on a bobbin; and

Fig. 8 is a sectional view taken on line 8--8 of Fig. 7.

Referring more specifically to the drawings by reference characters, 10 indicates the lay or support for the shuttle box 12 of a loom, the box being alternately moved or kicked from the full line position of Figs. 1 and 2 to the broken line position indicated at X by means of a rod 14, as is well known in the art. The box is adapted to carry upper and lower shuttles 16 within which are the bobbins 18, the bobbins, best illustrated in Fig. 7, embodying cores of wood or the like on which is wound the yarn 20. In the loom illustrated in the drawings, one of my electric feeler devices 22 is provided for each of the upper and lower bobbins 18, the two devices being mounted on brackets 24 bolted to the opposite sides of the support 10.

I will now describe the feeler device 22 which is illustrated in Figs. 1 to 4 and Figs. 7 and 8 of the drawings. The several parts of the device are carried by a metal supporting frame 26 which may be secured directly to the brackets 24 by bolts 28. Lower and upper contact elements or rods 30 and 32 are respectively carried in tubular members 34 and 36, the elements and members being in axial alignment with their adjacent ends in close proximity. The adjacent ends of the tubular members are connected to a block 38, the lower tube 34 being threaded directly into the block and the upper tube 36 being insulated therefrom by means of a bushing 40, of phenolic condensation product or the like, check nuts 42 and 44 being also provided to hold the members firmly threaded to the block. The tube 34 slides within a bore through the bottom of the frame 26 and the tube 36 slides within a like bore through a block 46 bolted to the

frame 26, the block 46 being insulated from the frame at 48 and the screw 50 serving as a binding post for a conductor 52.

The contact element 32 fits snugly within its tube and may be adjusted inwardly toward the element 30 by means of a screw 54 connected thereto and threaded into a bushing 56, in turn threaded onto the top end of the tube. The upper portion of the element 30 is of uniform diameter and fits with a close sliding movement within a bore in its tube. A collar 58 is formed on the lower portion of the element 30 and the bore within the tube 34 is enlarged at 60 to receive this collar and a spring 62. An L-shaped foot 64 is threaded onto the bottom or forward end of the tube 34 and a bore therethrough provides for the reception of the bobbin feeler portion 66 of the element 30, which portion projects forwardly of the collar and extends through the bore to provide a feeler point 67 projecting outwardly of the foot 64 and beyond its forward surface. The contact element 30 is normally held in its outermost position by the spring 62 and the block 38, with both tubes and their contact elements, is normally held in the foremost position by a spring 68 surrounding the tube 36.

The contact element 32 may be adjusted by the screw 54 to vary the gap between the two contact elements and it will be noted that such adjustment in no manner affects either of springs 62 or 68. Another novel feature of my invention is the adjustment of the contact element 30 whereby to vary the amount of the feeler point 67 projecting outwardly from the foot 64, it being understood that less point is required for fine yarn than for coarse yarn. The means which I have illustrated for the purpose comprises a wedge member 70 slidable within a bore 72 of the foot, the wedge being slotted at 74 and engaging oppositely disposed flats 76 on the portion 66. I also preferably provide a screw threaded stud 78 swiveled to the wedge at 80 for adjusting the latter as the stud is rotated. It will be readily appreciated that inward rotation of the stud 78 forces the element 30 inwardly and reduces the amount of point 67 exposed. Any change caused in the gap between the two elements by adjusting the screw 78 can be corrected by adjusting the element 32. It will be seen that the contact element 30 is grounded to the frame of the loom through the metal-to-metal contacts illustrated, while the contact element 32 is insulated therefrom. The parts may be protected by a housing 79 secured to the frame by screws 81.

The operation of the device is substantially as follows. The feeler or feeders 2 are so mounted that the point 67 and the relatively long bottom surface 65 of the foot 64 are engaged by the adjacent bobbin when the box 12 is kicked toward a feeler, the sides of the shuttle being open for this purpose, as seen in Fig. 2. Only a relatively small portion of the feeler is ordinarily exposed at 67 and this portion readily penetrates or sinks down into the yarn on the bobbin without causing any or sufficient movement of the element 30 to make a contact with the element 32. The portion 65 of the foot, however, contacts with the yarn along a substantial length of the bobbin and the pressure thereon releases pressure on the point 67 and causes compression of the spring 68. During this movement which compresses the spring 68, both contact elements 30 and 32 are moved as a unit and no contact takes place therebetween. However, when the yarn becomes sufficiently exhausted

from the bobbin, the point 67 directly engages the core thereof and, the pressure of the bobbin against the device not being relieved by engagement of the surface 65 with the yarn, the element 30 will be forced inwardly or rearwardly and cause a contact with the element 32. It will be understood that the contact thus made, operating through mechanism well known in the art and not a part of this invention, causes the shuttle to be automatically replenished with the yarn, as in Patent No. 1,549,008, or causes the machine to stop.

It will now be appreciated that the adjustment of the feeler point 67 is very important since the efficient and economic operation of the machine depends quite entirely on the amount of this point exposed. By the use of my fine adjustment of this point, the device can be so operated as to leave a much relatively smaller portion of yarn on the bobbin than has been heretofore possible. It will also be understood that the feeler point must be adjusted to correspond to the size of the yarn being used if efficient operation is to be secured and that my invention provides for a most minute adjustment for this purpose. The adjustment of the contact gap, by means of the element 32, also provides for greater efficiency and especially since this adjustment in no manner affects the action of the spring 62 on the feeler point. The bobbin 18 is ordinarily kicked against the feeler device with a considerable shock and for this reason the spring 62 may be relatively stronger than the spring 68 and still function with accuracy, since the engaging shock of the relatively hard core of the bobbin against the feeler point 67 is sufficient to overcome the spring 62 before effecting movement of the relatively heavy parts necessary to compress the spring 68. When the yarn is present on the bobbin this shock is absorbed thereby.

It will be understood that my invention can be embodied in various forms and in Figs. 5 and 6 of the drawings I have illustrated one modified form thereof. A contact element 82 is carried within a tubular member 84 slidable within the base portion of a metal supporting frame 86. A foot 64, the same as shown in Fig. 3, is carried on the outer end of the tube 84 and the element 82 is adjustable by means of a wedge therein, as shown in Fig. 7. The member 84 also slides through a bracket 88 on the frame 86 and is provided with a stop collar 90 for limiting outward or forward movement of the member under the action of a spring 92.

A second contact element 94, in the form of a screw, is carried by a plate 96 mounted on an insulation piece 98 carried by the member 84. A collar 100 limits outward movement of the element 82, and a spring 101 between the collar and an insulation bushing 103 serves normally to hold the element 82 projected outwardly and out of contact with the element 94. The element 82 is grounded to the frame 86 and a conductor 105 is connected to the element 94 through a binding post 107, a spring 109 and a plunger 111 in sliding contact with the plate 96, the binding post being carried on the frame 86 by an insulation piece 113. The parts may be protected by a housing 115 secured to the frame by screws 117.

The operation of this form of the device is substantially the same as that shown in Fig. 3 and heretofore described. Pressure on the foot 64 is adapted to compress the spring 92 and move the two contacts rearwardly as a unit, and inward movement of the element 82 relative to the foot 150

is adapted to compress the spring 101 and close the contacts.

Having thus described my invention, what I claim as new and desire to secure by Letters Patent is:

1. An electrical feeler comprising a metallic support, a contact element slidable therein and having a feeler point on one end thereof for engaging a bobbin, a second contact element substantially coaxial with the first element and normally out of contact therewith, one element being grounded to the support and the other being insulated therefrom, means connecting the two elements for movement together, means whereby the engagement of said point with the hard surface of a bobbin causes a direct engaging together of said contacts, and means adjacent to and disposed rearwardly of said point for engaging yarn on the bobbin whereby so to relieve pressure against the point as to eliminate closing of the contacts when a predetermined amount of yarn is on the bobbin.

2. An electrical feeler comprising a support, a tubular member slidably mounted therein, a contact element slidable within the member and having a feeler point on one end thereof for engaging a bobbin, a second contact element on the support, and substantially coaxial with the first element, means including said member connecting the two elements for movement together longitudinally of the member, means normally holding the elements out of contact, a relatively long foot carried by the tubular member and disposed rearwardly of said point for engaging yarn on the bobbin, and means permitting the elements to yield to pressure exerted against said point and foot without closing the contacts, the parts being so constructed that engagement of said point with the hard surface of a bobbin causes a direct engaging together of said contacts.

3. An electrical feeler comprising a contact element having a feeler point on one end thereof for engaging a bobbin, a second contact element coaxial with the first element, a spring coaxial with and normally holding the elements out of contact, a member adjacent to and disposed rearwardly of said point for engaging yarn on the bobbin, a second spring coaxial of and permitting the elements to yield to pressure exerted against said point and member without closing the contacts, the parts being so constructed that engagement of said point with the hard surface of a bobbin causes a closing of said contacts.

4. An electrical feeler comprising a contact element having a feeler point on one end thereof for engaging a bobbin, a second contact element, a spring normally holding the first element out of contact with the second element, a member operative against both elements and disposed rearwardly of said point for engaging yarn on the bobbin, means including a second spring permitting the elements to yield to pressure exerted against said member without closing the contacts, engagement of said point with the hard surface of a bobbin being adapted to cause a yielding of the first-named spring and closing of said contacts, and means providing for a relative adjustment of the elements to vary the gap therebetween without varying the tension on the first-named spring.

5. The combination set forth in claim 1, plus means for adjusting the second element to vary the gap between the elements.

6. An electrical feeler comprising a rod having a feeler point on the outer end thereof for en-

gaging a bobbin, a contact element carried by the rod, a sleeve slidably supporting the rod therein with the contact point end projecting outwardly from a relatively long foot on the outer end of the sleeve, a second contact element, means including said sleeve connecting the two elements for movement together longitudinally of the rod, a spring surrounding the rod and normally holding the first element out of contact with the second element, means whereby the rod may be adjusted inwardly to vary the amount thereof projecting outward from said foot, and means permitting the elements to yield to pressure exerted against said point and foot without closing the contacts, the parts being so constructed that engagement of said point with the hard surface of a bobbin causes a closing of said contacts.

7. An electrical feeler comprising a support, two contact elements, means mounting the elements for unitary movement on the support and having a foot for engaging yarn on a bobbin, a spring normally holding one element out of contact with the other element, means for adjusting the other element relative to the said one element to vary the gap therebetween, a feeler member cooperating with the said one element and projecting outwardly of the foot, a spring normally forcing the first-named means to the limit of its travel forwardly toward said foot, the second-named spring permitting pressure on said foot to force the first-named means rearwardly without closing the contacts and movement of the feeler member inwardly of the foot being adapted to engage the contacts, and means for adjusting the feeler member to vary the amount thereof projecting outwardly of the foot.

8. An electrical feeler comprising two contact elements in axial alignment, a spring acting axially on and normally holding one element out of contact with the other element, means for adjusting said other element axially relative to the said one element to vary the gap therebetween, means supporting the two elements for unitary axial movement and having a foot for engaging yarn on a bobbin, a feeler member cooperating with said one element and projecting outwardly of the foot, and a spring normally holding the second-named means and elements projected toward the foot, movement of said member inwardly of the foot being adapted to engage the contacts.

9. The combination set forth in claim 8, plus means for adjusting the feeler member to vary the amount thereof projecting outwardly of the foot.

10. In a loom, a shuttle box support, an electrical feeler disposed at one side thereof and comprising means having a foot for engaging yarn on a bobbin and carrying two contact elements in the feeler, a spring normally holding one element out of contact with the other element, means for adjusting the other element relative to the said one element to vary the gap therebetween, a feeler member cooperating with the said one element and projecting outwardly of the foot, a spring normally forcing the first-named means to the limit of its travel forwardly toward said foot, the second-named spring permitting pressure on said foot to force the first-named means rearwardly without closing the contacts and movement of the feeler member inwardly of the foot being adapted to engage the contacts, and means for adjusting the feeler member to vary the amount thereof projecting outwardly of the foot, the foot and member being

so located as to be engaged by the bobbin in the shuttle when the shuttle box is shifted laterally toward the feeler.

11. The combination set forth in claim 10, in which two feelers are respectively mounted on opposite sides of the support in positions to be engaged by adjacent bobbins when the shuttle box is shifted laterally toward the feelers.

12. An electrical feeler comprising a support, a tubular member slidably mounted therein and projecting outwardly therefrom, a relatively long foot on the outer end of the member, a contact element extending through the member and having a feeler point projecting outwardly beyond the foot, a second contact element connected to the member, a spring normally holding the elements out of contact but permitting inward yielding movement of the first element and contact thereof with the second element, and a spring normally holding said member projected toward the foot but permitting inward yielding movement thereof without engaging the contacts, the foot and feeler point being adapted to engage and sense a bobbin.

13. The combination set forth in claim 12, plus means for adjusting the feeler point to vary the amount thereof projecting outwardly of the foot, and other means for adjusting the gap between the elements.

14. The combination set forth in claim 12, in which the first element and said member are grounded to the support and the second element is insulated therefrom and provided with independent conducting means.

15. An electrical feeler comprising a contact element having a feeler point on one end thereof for engaging a bobbin, means having a relatively

long foot thereon and slidably supporting the element therein with the contact point end projecting outwardly from the foot, a second contact element, a spring surrounding and normally holding the first element out of contact with the second element, a wedge for adjusting the first element inwardly to vary the amount thereof projecting outward from said foot, a screw threaded member for actuating the wedge, and means permitting the elements to yield to pressure exerted against said point and foot without closing the contacts, the parts being so constructed that engagement of said point with the hard surface of a bobbin causes a closing of said contacts.

16. An electrical feeler comprising a contact element having a feeler point on one end thereof for engaging a bobbin, means having a relatively long foot thereon and slidably supporting the element therein with the contact point end projecting outwardly from the foot, a second contact element, a spring surrounding and normally holding the first element out of contact with the second element, a wedge for adjusting the first element inwardly to vary the amount thereof projecting outward from said foot, said wedge being slotted and engaging oppositely disposed flats on and preventing rotation of the element, a screw threaded member swiveled to and acting to adjust the wedge in opposite directions, and means permitting the elements to yield to pressure exerted against said point and foot without closing the contacts, the parts being so constructed that engagement of said point with the hard surface of a bobbin causes a closing of said contacts.
